COVER MECHANISM

Lawrence A. Althoff, Chicago, Ill.

Application August 8, 1938, Serial No. 223,752

5 Claims. (Cl. 126—214)

This invention relates to cover mechanism, and more particularly to means by which a side-equipped cover may be supported upon a frame, such as a range or stove frame, connecting mechanism being employed for preventing the cover from moving rearwardly in the raising operation. For the purpose of illustration the invention is described in connection with a stove frame, although it will be understood that the cover may 10 be used with other frames.

An object of the invention is to provide cover supporting and connecting means whereby the cover may extend to the rear of the frame and be raised and lowered without shifting the body 15 of the cover rearwardly. A further object is to provide cover hinging and connecting means whereby the lower rear edge portions of the sides of the cover are permitted to move forwardly and rearwardly, while the main body or top of the 20 cover is guided against any substantial rearward movement. A further object is to provide a cover for a stove or range whereby the side-equipped cover is permitted to extend to the rear side of the stove frame, while at the 25 same time the cover is prevented from extending farther rearwardly during the raising and lowering of the cover. Other specific objects and advantages will appear as the specification proceeds.

30 The invention is illustrated in a preferred embodiment by the accompanying drawings, in which—

Figure 1 is a perspective view of a stove equipped with a cover embodying my invention, the cover being supported in raised position; Fig. 35 2, an enlarged broken plan view of the structure shown in Fig. 1; Fig. 3, a transverse sectional view, the section being taken as indicated at line 3 of Fig. 2; Fig. 4, a sectional detail view, the section being taken as indicated at line 4 of Fig. 2; Fig. 5, a transverse sectional view, the section being taken as indicated at line 5 of Fig. 2; and Fig. 6, a perspective view of the guide bracket carried by the stove top.

45 In the illustration given, A designates a stove top, and B designates the side-equipped cover.

The stove top A may be of any suitable type or construction. It is provided at its rear side with the usual extension supporting pipe 10. 50 Along each side of the top and near the rear thereof are bracket depressions 11 formed in the casting at the top. These depressions are adapted to receive the bottom plate 12 of each of the guide brackets 13. Each plate 12 fits snugly within the recess 11 and is bolted to the top

5 A by the bolts 14, as shown more clearly in Fig. 5, the top of the plate 12 being flush with the top surface of the stove top A.

The guide bracket member 13 extends vertically and at right angles to the plate 12 with which it is integrally formed. An upwardly extending portion of the guide bracket 13 is provided with a guide slot 15 which extends upwardly and rearwardly with respect to the top A of the stove. At its forward end, each bracket 13 is provided 10 with a roller stop or roller socket 16.

The side-equipped cover B may be of any suitable form or construction. In the illustration given, it comprises a top cover member 17 and side members 18. The top member 17 and the 15 side members 18 may be secured together by any suitable means. In the illustration given, the top member 17 is provided at its front and rear sides with depending integral posts 19. The sides 18 are provided with inwardly extending flanges 20. 20 Bolts 21 pass through the flanges 20 and engage the internally threaded posts 19 to lock the parts together.

The top members 17 of the cover support near each side thereof depending guide pins 22 which 25 engage the guide slots 15 of the brackets 13. As shown more clearly in Figs. 2 and 3, the pin 22 is formed integrally with a depending arm 23, and the arm 23 is formed integrally with a flange 24 which extends at right angles to arm 23. The 30 inner edge of flange 24 abuts a guide rib 25 formed with the top 17. The flange 24 is secured to the top 17 by a bolt 26.

Each of the side walls 18 is provided at its rear and lower edge with an integrally formed and 35 inwardly extending boss 27. The pin 28 is supported by boss 27, and a roller 29 is carried by pin 28. The roller is thus adapted to be moved rearwardly along the inset plate 12.

The cover member B is provided at its front 40 side with a handle-equipped front 30. At its rear the top member 17 is provided with an integral downwardly extending side 31, the central portion of the side 31 being inwardly bowed slightly so as to provide a recess for the 45 chimney 10.

Operation

In the operation of the cover, assuming that it is in raised position, as illustrated more clearly in Figs. 1, 2 and 4, the roller 29 extends under the roller stop 16, while the traveling guide pin 22 extends through the lower portion of the guide slot 15. As the cover is lowered, the guide pin 22 rises within vertical slot 15, while at the same 55

time each of the rollers 19 moves rearwardly. In this operation, the pivot is formed by the upwardly moving pin 22 within slot 15 and about this pivot the lower roller-equipped ends of the sides 18 move. While the rollers move all the way from the front position shown in Fig. 4 to a position at the extreme rear of the cover, the pins 22 move only a slight distance to the rear of the vertical, as outlined by the shape of slot 15. When the cover is again raised the rollers 23 advance forwardly along plates 12 to the position shown more clearly in Fig. 4, while simultaneously the pivot pins 22 move downwardly along the slot 15.

15 With the construction illustrated it will be clear that while the top cover member 17 rises during the lowering movement of the cover so as to permit the sides 18 to clear the stove top A, the cover member 17 swings about a traveling 20 pivot which operates in a slot almost vertical. Thus there is substantially no rearward movement of the cover B as it swings to lowered position or to raised position.

The construction is extremely simple while at 25 the same time enabling the cover to extend to the rear of the range frame. Here movement of the cover is accomplished without causing the cover to move rearwardly into contact with the stove pipe carried by the pipe supporting extension.

30 While in the illustration I have shown a specific and detailed structure for accomplishing the results described, it will be obvious that such structure may be readily modified by those skilled 35 in the art without departing from the spirit of my invention.

The foregoing detailed description has been given for clearness of understanding only, and no unnecessary limitations should be understood 40 therefrom, but the appended claims should be construed as broadly as permissible, in view of the prior art.

I claim:

1. In combination with a frame equipped with 45 a pair of upwardly extending spaced brackets, each bracket having a vertically extending guide slot and a roller socket, and a side-equipped cover having rollers adapted to engage said roller socket when the cover is in raised position, locking 50 said cover against rearward and vertical movement, said cover being also provided with guide

pins engaging said slots, said pins being adapted to move downwardly when said cover is raised.

2. In combination with a frame equipped with a pair of upwardly extending and spaced brackets, each bracket being provided with a vertically extending guide slot and with a horizontally extending roller socket, and a side-equipped cover provided with a roller adapted to be received within said socket when the cover is in raised position, said cover being also provided with depending 10 guide pins engaging said slot and cover with said roller for preventing rearward movement of said cover when the same is raised and lowered.

3. In combination with a frame equipped with an upright bracket having a rearwardly inclined 15 slot therein, a cover having depending sides equipped at the rear lower portions with anti-friction members horizontally movable on said frame beneath said slot, and a guide pin supported by said cover and depending therefrom 20 for engagement with said slot.

4. In a stove provided with a pipe at the rear thereof, a side-equipped cover for said stove, a bracket carried by said stove at each rear side thereof, each bracket being provided with a vertically and a rearwardly extending slot and at its forward side with a roller socket, and said sides of said cover having rear portions provided with rollers adapted to engage said roller sockets when the cover is in raised position, said cover 30 being provided also with depending guide pins engaging said slots.

5. In combination with a frame equipped with a pair of upwardly extending spaced brackets provided with base members sunk in said frame 35 and becoming a part of the upper surface thereof, each bracket also being provided with a vertically and rearwardly extending guide slot and a substantially horizontal roller socket, a cover having depending sides, said sides being equipped 40 at the rear lower portions thereof with rollers engaging said frame, said rollers being horizontally movable along said frame beneath said slots and adapted to be received within and beneath the upper wall of said sockets when said cover 45 is raised, said cover being also provided with guide pins for engagement with said slot, said pins being moved upwardly therein when said cover is lowered.

LAWRENCE A. ALTHOFF. 50
